UNITED STATES PATENT OFFICE

2,574,563

PORTABLE CLOTHESBASKET

Herbert Hieb, Des Moines, Iowa, assignor of one-half to Elwin L. Wolf, Des Moines, Iowa

Application August 2, 1948, Serial No. 41,932

2 Claims. (Cl. 150—49)

1

The principal object of my invention is to provide an elevated container that may be used either as a clothes hamper or clothes carrying device.

A further object is to provide a clothes or like hamper that is sanitary, of light weight, and rust proof.

A still further object of this invention is to provide a hamper that when not in use, may be folded for compact storage.

A still further object of this invention is to provide a transportable clothes hamper that has no sharp edges or points to catch or damage either the user or the clothes of the user.

A still further object of my invention is to provide a portable elevated hamper or like that due to its elevation eliminates substantially all stooping or bending heretofore required of a housewife doing a washing.

A still further object of my invention is to provide a clothes hamper having a fabric container and metal support that is so designed that when folded and lifted, the fabric container will be properly held and supported within the metal frame regardless of the angle the frame is held.

A still further object of my invention is to provide a clothes hamper that is refined in appearance, durable in use, and economical in manufacture.

These and other objects will be apparent to those skilled in the art.

My invention consists in the construction, arrangement, and combination of the various parts of the device, whereby the objects contemplated are attained as hereinafter more fully set forth, pointed out in my claims, and illustrated in the accompanying drawings, in which:

Fig. 1 is a perspective view of my device ready for use.

Fig. 2 is a top plan view of the device and more fully illustrates its construction.

Fig. 3 is a side view of my hamper in folded condition.

There have been many types of hampers sold to the general public. Most of them have been objectionable for one reason or another. Usually they are of the non-collapsible type that rests on the floor. As such, they are difficult to pick up and carry, and this especially true when they are used to carry wet washed clothes from the basement to the drying line. Even after reaching the clothes drying line they are objectionable, as it is necessary to stoop over to get each individual washed item prior to hanging the same on the line. These two objections are most important when it is realized that most clothes are washed in the basement, carried up a flight of basement steps, and then hung on an outside drying line. Not only are such hampers lacking in utility, but are the cause of serious falling accidents on the basement steps. Still another objection to such hampers is their weight. To elim-

2

inate such excessive weight, some hampers are made of wicker or like weave. However, even these are objectionable, in that they can not be safely carried at the side of the user, are non-foldable, and usually have a supporting bench or means which certainly can not well be packed along with the hamper when the hamper with clothes is being brought up from the basement. Furthermore, such wicker splinters, and provides dangerous slivers capable of damaging both user and the user's clothes. I have overcome all such objections by providing a light, one unit, folding hamper which I will now describe in detail.

The numeral 10 designates an inverted U-shaped frame preferably of aluminum tubing or aluminum pipe. The numeral 11 designates a second inverted U-shaped frame similar to the frame 10 except its center portion is slightly less in width so that the frame 11 can operate inside the frame 10 as shown in the drawings. Also the side leg portions of the frame 11 are slightly longer than the side leg portions of the frame 10. When the device is in open condition as shown in Fig. 1, the two leg portions of the frame 10 will cross the two leg portions of the frame 11, thereby forming an X support at each side. Any suitable means may be used to pivot the leg portions of the two frames together at the point where they cross each other. In the drawings I show a rivet 12 extending through each side pair of cross legs. On the ends of the two legs of the frame 10 I secure wheels 13, and on the ends of the two legs of the frame 11, I secure rubber or like socket feet 14. Obviously, if desired, wheels may be mounted on the ends of all the legs, or the feet 14 may be used on all four legs. To limit the opening movement of the top of the device, I have connected a chain 15 to each pair of crossed side legs and at a point substantially below the pivot point of the legs as shown in Fig. 1. As each chain has one end fastened to a leg of the frame 10 and a leg of the frame 11, the length of the chain and its position relative to the pivot point will determine the spread of the upper portions of the two frames 10 and 11. The two frames 10 and 11 form the master foldable frame unit for holding the fabric hamper 16. This hamper 16 may be made of any suitable flexible material such as canvas, and when open is roughly a container of rectangular appearance. At each of the two top ends of the hamper is a flap 17 designed to extend over and around the two center portions of the frames 10 and 11 respectively. Any suitable means may be employed to secure these flap ends around and to the frames 10 and 11. In the drawings I use ordinary separable glove snap fasteners 18 on the flaps and rim base of the hamper 16. By this means it is a simple matter to remove or replace a hamper on the frame unit. By this construction the bag or hamper will be supported between the extended central portions of the frames

10 and 11, as shown in Fig. 2. Due to the chains 15, the hamper will not limit the opening of the frame unit, thereby the hamper will not be unduly stretched nor torn. As the hamper is flexible, the frame unit may be collapsed as shown in Fig. 3. This is desirable for shipping and storage purposes, but is even more desirable for carrying purposes. This is especially true when the device is used for carrying clothes or like. However, when any weight is in the hamper and the frame unit is folded and lifted to an angle as shown in Fig. 3, the tendency of the bag is to swing, sidewardly or downwardly or forwardly, or slide on the frame unit, and if this were permitted it would be dangerous and almost impossible to control the device when carrying. My method of preventing this is an important feature of my invention and consists of sewing or like securing a band 19 to each of the sides of the hamper as shown in the drawings. These bands are secured at each end and extend horizontally to the outer side of the pair of frame legs adjacent to it. When the device is picked up as shown in Fig. 3, the top band will come into play and support and align the hamper properly in the frame unit. If the device is turned over, the other band will become uppermost and will thereupon come into effective use. By this arrangement the folded hamper device, by grasping either pair of side legs, may be easily carried with its load at the side of the user, thereby not only facilitating its portage, but providing an unobstructed view forward of the user. This is especially desirable when going up or down stairs and when it is necessary that the user be able to see each step. Because of its light weight, the entire device is moved as a unit. This means that the user, whether in the basement or at the clothes line will have an open elevated clothes container. By having the legs of the frame 11, longer than the legs of the frame 10, they will strike the floor or like prior to the time the wheels on the frame 10 strike. This eliminates any skidding of device when it is set down, either in folded or expanded condition. By the frame being of aluminum, it is light and rust-proof for basement use. Although I have described my device as a clothes hamper, obviously, it can be used for many other purposes. In the drawings I show the bands 19 as extending around both of the frame legs. If desired, such bands may extend around only one of the legs, or if two bands are used at each side, one band may be used in conjunction with each of the legs. Regardless of this construction, however, care must be exercised to permit the removal of the bands from the leg or legs when the bag is removed for certain purposes. Therefore, unless the band embraces the leg below the pivot point 12, the band should be detachable at one end by a suitable fastening means, such as a glove snap fastener.

If the bag is constructed in accordance with the disclosure in Fig. 1, the band will move slidably over the legs both laterally and longitudinally thereon. For this reason, as is clearly disclosed in Fig. 3, the collapsing of the frame while it closes the top of the bag, in no way restricts or otherwise reduces the capacity of the lower portions of the bag. Therefore, while the bag is readily collapsible for carrying purposes and is retained within the frame by strap 19 when carried in a collapsed condition, the strap does not limit the amount of clothes that may be carried in the bag.

Some changes may be made in the construc-

tion and arrangement of my clothes or like hamper without departing from the real spirit and purpose of my invention, and it is my intention to cover by my claims, any modified forms of structure or use of mechanical equivalents which may be reasonably included within their scope.

I claim:

1. A portable clothes basket of the type wherein two inverted U-shaped frame members are pivoted together at an intermediate point in their respective legs and may be collapsed or opened to support a flexible bag member having two opposite top ends secured to the center portions of said U-shaped frame members respectively; said portable clothes basket characterized by having said opposite upper ends of its flexible bag secured to the center portions of said U-shaped frame, and a band secured at each end to one end of said flexible bag and with said bag loosely and slidably embracing the leg portions of said U-shaped frame members adjacent the same end of said flexible bag to which said band is secured whereby the frame members may be placed in open or collapsed condition without affecting the capacity of the lower portion of the bag, and whereby the flexible bag is retained by the band in substantially a centrally located position between the opposite pairs of legs of the frame members when the frame is collapsed and the unit is carried by grasping the frame members overlapped by the said band.

2. A portable clothes basket of the type wherein two inverted U-shaped frame members are pivoted together at an intermediate point in their respective legs and may be collapsed or opened to support a flexible bag member having two opposite top ends secured to the center portions of said U-shaped frame members respectively; said portable clothes basket characterized by having said opposite upper ends of its flexible bag detachably secured to the center portions of said U-shaped frame, and a band secured at each end to one end of said flexible bag and with said bag loosely and slidably embracing the leg portions of said U-shaped frame members adjacent the same end of said flexible bag to which said band is secured whereby the frame members may be placed in open or collapsed condition without affecting the capacity of the lower portion of the bag, and whereby the flexible bag is retained by the band in substantially a centrally located position between the opposite pairs of legs of the frame members when the frame is collapsed and the unit is carried by grasping the frame members overlapped by the said band, and whereby the bag may be removed from the frame by detaching its upper end and sliding the same downwardly on the frame until the said band clears the lower end of the leg members it normally overlaps.

HERBERT HIEB.
